MERCHANDISE DISPLAY STAND

Jay Doblin, New York, N. Y., assignor to The National Biscuit Company, New York, N. Y., a corporation of New Jersey

Application May 5, 1955, Serial No. 35,821

Term of patent 14 years

(Cl. D80—9)

The dominant features of my design reside in the portions shown in full lines, the rear being substantially plane.

I claim:

The ornamental design for a merchandise display stand, as shown and described.
